UNITED STATES PATENT OFFICE.

FREDERICK SEDGWICK, OF CHICAGO, ILLINOIS.

ELECTRIC MECHANISM FOR OPERATING SAFE BOLT-WORK.

SPECIFICATION forming part of Letters Patent No. 329,223, dated October 27, 1885.

Application filed March 10, 1885. Serial No. 158,308. (No model.)

To all whom it may concern:

Be it known that I, FREDERICK SEDGWICK, of Chicago, in the county of Cook and State of Illinois, have invented certain new and useful Improvements in Electric Mechanism for Operating Safe Bolt-Work, of which the following is a description, reference being had to the accompanying drawings, in which—

Figure 1 is a view of the inside of a safe-door, showing my improved mechanism applied thereto and connected with the bolt-bar. Fig. 2 is a horizontal sectional view in plan of a safe-door to which said mechanism is attached; and Fig. 3 is an end view of said mechanism, showing a part of the door in section.

Like reference-letters indicate like parts in the different figures.

The object of my invention is to provide an electrical mechanism whereby the bolt-work of safes may be thrown and retracted from the outside, thereby rendering said safes more secure by dispensing with spindles or other mechanical appliances which necessitate having a hole or holes through the door for their reception. I accomplish said object by means of one or more electro-magnets attached to the inside of the safe-door, and having suitable electrical connections with a battery-cup 25 and a circuit-breaking device upon the outside, said magnets being adapted, when excited, to operate suitable mechanism connected with the bolt-work, and thus throw or retract the same, substantially in the manner hereinafter more particularly described and claimed.

In the drawings, A represents a plate of metal or any suitable frame-work, which may be attached by bolts or screws to the inside 40 of the safe-door B, said frame having cast or otherwise rigidly attached thereto brackets a a', Fig. 2, to which is secured, by means of screws, an electro-magnet, C, connected by a wire, c, with a binding-post, c', from which a wire, c', Fig. 2, is carried through the safe-door B, whence it connects preferably with a binding-post, c', attached to a vulcanite plate, E, secured to the safe-door, said wires c c' being properly insulated. The terminal 45 wire c' is connected by a screw, c', to the frame or plate A, which has a metallic connection with the safe-door B, into the outer plate of

which a binding-post, c⁶, is screwed, as shown, by which said magnet C may be connected with a battery, F, through a circuit-wire, c⁷, and circuit-breaker or push-button C'', which is in turn connected with the binding-post c³ by wire c⁸, thereby enabling the circuit to be completed with the battery F and magnet C by pressing the button C'' in the usual way. 55

Upon the ends respectively of the bracket a and plate A are extensions or lugs a² a², which form bearings for a rod, a³, by means of which is loosely pivoted or suspended an armature, D, attached thereto, and provided 60 with a rigid extension or pendent arm, d, Figs. 1 and 3, the normal position of which is vertical. To the lower end of said arm is attached a gravity-pawl, d', which is sustained normally in a horizontal position, substantially as shown, by a stud or pin, d², attached to the plate A, said pawl being adapted to engage a ratchet-wheel, G, having a pinion, g, which forms one of a train of gears of any desired number, according to the power required, terminating in a wheel, H, to which is attached a pitman, h, connecting by means of a wrist-pin, j, to the bolt-bar J. A spring-stop, g', is attached to the plate A, so as to engage with the teeth of the ratchet-wheel G 75 and regulate its movement by preventing the same from going too far forward or back. 80

Upon pressing the button C'' the magnet C is excited and attracts the armature D, thus actuating the pawl d' and moving the ratchet-wheel one notch. As soon as the circuit is broken by releasing the button, the arm d by virtue of its own gravity assumes a vertical position, and draws the pawl d' back in position for a second engagement, so that by manipulating the button C'' the wheel H is caused to make a half-revolution, thus throwing the bolt-work, while a further manipulation completes said revolution and retracts said bolts, as shown in the drawings. 90

The above-described device may serve as a valuable auxiliary in connection with my improved mechanism for operating safe bolt-work by means of compressed air, for which application for Letters Patent is filed here-with, in case said mechanism should from any cause fail to act, which combination may form the subject of a separate application. 100

Having thus described my invention so as

to enable others skilled in the art to exercise the same, I claim as new—

The combination, with the bolt-work of a safe, of the magnet C, electrically connected with a circuit-breaker, C", and battery-cup, an armature attached to a loosely depending arm provided with a pawl arranged to engage a ratchet-wheel, and means, substantially as

shown, for connecting the latter with said bolt-work, substantially as described, and for the purposes specified.

FREDERICK SEDGWICK.
